UNITED STATES PATENT OFFICE.

HUGO BOHL, OF WESTFIELD, NEW JERSEY, ASSIGNOR TO RADIANT LIGHTING FIXTURE CO., OF NEW YORK, N. Y., A CORPORATION OF NEW YORK.

DESIGN FOR A FRAME FOR LANTERNS.

Application filed January 16, 1926. Serial No. 16,117. Term of patent 3½ years.

To all whom it may concern:

Be it known that I, HUGO BOHL, a citizen of the United States, residing at Westfield, in the county of Essex and State of New Jersey, have invented a new, original, and ornamental Design for a Frame for Lanterns, of which the following is a specification, reference being had to the accompanying drawing, forming part thereof.

Fig. 1 is a front elevation showing my new design; and Fig. 2 is a side elevation thereof.

I claim:

The ornamental design for a frame for lanterns, as shown.

HUGO BOHL.
